UNITED STATES PATENT OFFICE.

ARTHUR D. RAMSAY, OF LOWELL, MASSACHUSETTS.

BOX FOR BOBBIN TRUCKS.

Application filed January 23, 1923. Serial No. 614,458.

To all whom it may concern:

Be it known that I, ARTHUR D. RAMSAY, a citizen of the United States, residing at Lowell, in the county of Middlesex and 5 State of Massachusetts, have invented certain new and useful Improvements in Boxes for Bobbin Trucks, of which the following is a specification.

This invention has to do with boxes for 10 the empty bobbins which are used on slubbing, fly, and spinning frames by the doffer when the filled bobbins are removed.

Such slubbing, fly, and spinning frames may have from 50 to 160 spindles on each 15 side, and these frames are arranged in alleys as close together as possible to avoid waste space.

Before the frame is started, each spindle is equipped with an empty bobbin, and 20 when these are filled it is necessary to stop the frame and remove the filled bobbins. In practice, it is found easiest to remove the filled bobbin and replace it with an empty bobbin at the same time, in preference to removing all the filled bobbins 25 and then going back over the ground with empty bobbins.

For convenience, one girl goes along the 30 line of spindles leaving empty bobbins on any convenient part of the frame and then, going back, takes an empty truck to be filled with full bobbins and pushes this ahead of her. As she goes along she removes the 35 flyer, which she places on the top of the frame, then the full bobbin, which she throws into the truck, and takes an empty bobbin from those previously put on the frame and puts it in place of the full bobbin. Behind her follows another girl who 40 takes down the flyer, puts it in place and ties up the ends of the yarn.

On these frames, there is a top shelf on 45 which the flyers are placed, and below this and under the roving is another shelf which is the only available space where the empty bobbins can be placed. In putting these empty bobbins in between the strands of rapidly-moving roving and taking them out, there is great danger of breaking the 50 roving, and as the bobbins are not clean the roving picks up fly and other impurities making uneven yarn.

The purpose of my invention is to provide 55 a box for empty bobbins which can be attached to the truck for carrying the full bobbins in such a way and of such construc-

tion that it is not necessary to put the empty bobbins on the shelf in advance of the doffer, thus saving one entire operation.

As these trucks full of full bobbins and 60 others entirely empty are traveling around to different parts of the mill, it is desirable that my box should be detachable and of such construction and weight that a woman or girl can move it around from one truck 65 to another.

In the drawings, Figure 1 is an elevation showing part of a fly, roving or slubbing frame and part of the alley between it and the adjoining frame, with a truck having 70 one of my boxes attached in the alley.

Fig. 2 is a perspective elevation of a truck with my preferred form of box attached.

Fig. 3 is a sectional elevation on the line 75 3—3 of Fig. 2.

Fig. 4 is a view from one end or side of my box with the front of the cover for the mechanism removed.

Fig. 5 is a sectional detail showing the 80 pulley, flexible member and grooves.

Fig. 6 is a perspective showing another modification of my box as applied to a different type of truck.

In the drawings, M represents what may be a roving frame or a spinning frame 85 which has two rows of spindles 10, 10 which carry the removable flyers 11, 11 and the bobbins 12, 12.

The roving R passes down underneath cover 16 and above beam 17 between the 90 rollers 15, 15, and is divided into two lines 13 and 14 each one of which passes into the top of a flyer such as 11 and 11.

In the ordinary doffing of these frames, full bobbins, such as 27, are thrown into 95 the truck A, while the doffer, as she moves along, lifts off flyers 11 and places them on the cover for the drawing rolls 16, as shown at 19, after having previously passed down the line and inserted empty bobbins, 100 such as 18, on the roller beam 17. It is obvious that these bobbins 18, as shown by the dotted lines, must be passed between the rows of roving 13 and 13, or 13 and 14, and as these are not over two inches apart 105 they are likely to be struck when placing the bobbin on the shelf and when removing it.

The truck, such as A, has the sides 20, 21, back 22, front 23, floor 24, middle wheels 110 25 and front and back wheels 26, 26, all of well known construction.

My box B is substantially rectangular and has sides 30 and 31, front 33 and back 32, together with bottom 129 and, preferably, at one end the small rollers 130 whereby it 5 can be easily dragged around.

By means of hooks or angle irons 34, my box can be attached to the front end 23 of truck A and can readily be removed by lifting. As it is necessary that the distance from front 33 to back 32 should be small so that the girl can conveniently reach over it into the truck A, and as it is necessary that the depth of box B should be two feet or more in order to carry the necessary 15 number of empty bobbins and in order to avoid the necessity of a doffer leaning over, I find it necessary to provide a false bottom 35 suspended on flexible members 37 and 38 which pass over pulleys 42 and 43, each placed at the top on an end 30 or 31, preferably, in a groove 36, through which groove a member 37 or 38 passes, thence being attached to the false bottom.

The other end of each flexible member 37 and 38 is attached to a grooved pulley, such as 51 or 52, carried by the end of shaft 50 which extends through the box.

At one end of this shaft is a ratchet wheel 53 which turns with the shaft and with the 30 pulleys 51 and 52.

As a means of operating the ratchet, shaft, and pulleys, I prefer to provide a driving pawl 70, in engagement with the ratchet wheel, pivoted at 71 to the foot lever 35 F and at 72 to a rod 73 supported in a bearing 76 attached to foot lever F and having a collar 74 between which and 76 is a compression spring 75 which normally keeps the pawl and ratchet in engagement.

The end of rod 73 is normally in position directly in front of the swinging end 81 of a release lever L.

Foot lever F is loose on shaft 50, which serves as a pivot and has a pedal 77 which 45 extends outside the box, as shown in Fig. 2, within convenient reach of the operator's foot. A returning spring S attached to box B at 84 and to pedal F at 85 normally keeps the pedal raised, ready to be depressed by the foot at will when it is desired to wind up the flexible members 37 and 38 on the pulleys 51 and 52.

I also provide a check pawl 60 pivoted to the box B at 61 and having a tail pivoted at 62 to a release rod 63 which passes through the bearing 66 attached to the box. This check pawl also has a collar 64 between which and bearing 66 is a spring 65 whereby it is normally kept in engagement with ratchet wheel 53.

The release lever L projects up above the cover 40 within convenient reach of the

hand of the operator, and is pivoted at 80 with its free end 81 in such position that when lever L is pulled over to the back it 65 disengages both pawls 60 and 70 allowing the false bottom 50 to drop by its own weight. Returning spring 87 brings lever L back to position.

In Fig. 6, I show how my box B can be 70 used with a truck, such as R, having a flat top or floor 110 supported by middle wheels 111 and end wheels 112 in a well known manner. My box is the same as shown in Fig. 2 but has an eye 113 on each side into 75 which a hook 114 on the truck can be forced so as to hold it in place. This is for the empty bobbins and is particularly useful in the spinning room where, instead of a large box on wheels, such as A in Fig. 2, 80 several small light boxes, such as P, P shown in Fig. 6, can be used.

For use in a spinning room where the bobbins are taken to looms, it is more convenient to have such boxes P with handles 85 115 of a size to be conveniently carried around and placed one at each loom.

I claim:

1. The combination in a box for empty bobbins, of rollers at the bottom, and means to attach it to a truck, with a vertically 90 slideable false bottom, and means for raising and lowering and for holding such false bottom in position, including a drive shaft, lifting pulleys fixed thereto, a ratchet wheel fixed to said shaft, a check pawl in engagement therewith, means to throw such check pawl out of action, a driving pawl in engagement with said ratchet wheel, foot operable means for operating said driving pawl, top pulleys located at the top of the 95 box, and flexible members which pass over such pulleys and connect at one end with such false bottom and at the other end with said lifting pulleys.

2. The combination in a box for empty bobbins, of means to attach it to a truck, with a vertically slideable false bottom, and means for raising and lowering and for holding such false bottom in position, including a drive shaft, lifting pulleys fixed thereto, a ratchet wheel fixed to said shaft, a check pawl in engagement therewith, means to throw such check pawl out of action, a driving pawl in engagement with 100 said ratchet wheel, foot operable means for operating said driving pawl, top pulleys located at the top of the box, and flexible members which pass over such pulleys and connect at one end with such false bottom and at the other end with said lifting pulleys.

ARTHUR D. RAMSAY.
